UNITED STATES PATENT OFFICE.

OSCAR M. LEICH, OF GENOA, ILLINOIS, ASSIGNOR TO LEICH ELECTRIC COMPANY, OF GENOA, ILLINOIS.

ELECTRIC-CONTACT-OPERATING DEVICE.

Application filed April 24, 1918. Serial No. 230,447.

To all whom it may concern:

Be it known that I, OSCAR M. LEICH, a citizen of the United States, residing at Genoa, in the county of De Kalb and State 5 of Illinois, have invented a certain new and useful Improvement in Electric-Contact-Operating Devices, of which the following is a full, clear, concise, and exact description, reference being had to the accompanying 10 drawings, forming a part of this specification.

My invention relates to electric contact operating devices and has to do more particularly with devices of this character employed as alternating current rectifiers, one of the objects of my invention being to provide a simple and inexpensive machine, easy to maintain and steady in its operation. A further object of my invention is to provide 15 a vibratory device of this character having a polarized electromagnet adapted to be actuated by alternating current and whose armature is supported by a pivotally mounted free operating shaft carrying a 20 multiple-contact operating-plate vibrating in synchronism with the impressed current so as to cut in and out on the wave at the proper time in order to supply a rectified or unidirectional current, that is, a current flowing 25 in one direction. Although in the preferred application of my invention I have shown it as a rectifier, it is to be understood that it is not limited to such use, as I contemplate applying it in other ways.

30 In my application Serial No. 139,397 filed December 28, 1916, Patent No. 1,324,742, patented Dec. 9, 1919, I have shown and am claiming a multiple rectifier, the present case being in some respects an improvement over 35 the said application.

I understand that vibratory rectifiers of different kinds have already been produced but there are certain objections to these devices which my invention overcomes.

40 My invention is particularly useful where a cheap and simple device is to be used, a further advantage being that it may be set into operation and run for long periods with comparatively little attention, being useful 45 in telephone exchanges, garages and like places where an inexpensive effective device is needed for charging storage batteries from the alternating current main. One of

the difficulties in the construction of a machine of this character is to provide a cheap 55 small machine of comparatively large output as the amount of current which may flow through any single contact is of course limited, but to overcome this I have provided a multiple-contact operating-device which 60 is quite positive in effecting a simultaneous operation of a plurality of contacts connected in multiple. It is quite important in a device of this character that the multiple-contacts be practically simultaneous in their 65 operation so as to all get the full amount of the predetermined portion of the current wave. By providing each of the multiple-contacts with a protective resistance the combined resistance is comparatively low 70 although each contact is individually protected. One of the objections to the ordinary device in which a spring mounted armature is provided, is that the resiliency of the spring mounting varies. Thus the 75 armature tends to operate out of step with the impressed alternating current as the pitch of the tongue or reed varies. This, of course, causes improper operation of the contacts so that the output of the machine 80 is affected. That is the output may vary, or the direction of current alternate. In order to overcome this objection I have provided a pivoted freely operable armature, that is an armature preferably normally 85 free of spring tension which would tend to tune the armature, as in the case of a spring mounted device. This free operating armature carries a multiple-contact operating-plate and it is quite important that these 90 moveable elements of the device be freely operable but without any undue play during normal operation. Therefore I provide an automatic adjustable bearing for the armature shaft so that the wear of the bearing 95 is taken up as it occurs and a proper alignment of the contact operating plate and contacts maintained.

For a better understanding of my invention reference is to be had to the accompanying drawings in which:

Fig. 1 is a face view of a preferred form of my invention;

Fig. 2 is a vertical cross-section along the line 2—2 of Fig. 1, showing the mounted 105 position of the device as secured to the wall;

Fig. 3 is a top plan view of Figs. 1 and 2; Fig. 4 is an enlarged cross-sectional view along the line 4—4 of Fig. 3;

Fig. 5 is an enlarged cross-sectional view 5 along the line 5—5 of Fig. 3; and

Fig. 6 is a diagrammatic view of the machine connected to an alternating current line circuit and a storage battery which is being charged.

10 Referring now more particularly to the preferred form of my invention it comprises an insulated base 10 secured to suitable wall brackets 11, said base carrying a plurality of resistance holders preferably in the form 15 of lamp sockets 12 which are connected in common by a metal strip 13. A condenser 14 is suitably fastened to the rear of the base 10.

At the front of the base 10, I provide an 20 electro magnet preferably in the form of a polarized device including a pair of vertically positioned coils 15, 16 which are connected together at their rear or lower ends by means of a yoke 17 of non-magnetic material which in turn is secured to a bracket 18 suitably fastened to the base. A heel iron 19 is attached to the core of each spool and supports a permanent magnet 20 which extends adjacent the operative end of the 25 corresponding spool, like poles being preferably positioned at the free ends of these magnets 20. The operating ends of the spool cores are connected by means of a non-magnetic bracket or plate 21, the ends of the 30 cores being threaded and carrying lock nuts 22 which clamp against opposite faces of the plate 21, the operative ends of the spool cores thus being adjustable relative to the armature. The connecting plate 21 also 35 supports the contact operated mechanism, said plate being provided with a pair of bearing supports or ends 23, 24 which are positioned transversely of the operating poles.

40 As previously referred to I provide a novel automatically adjustable bearing for the armature shaft but this broadly has been made the subject of a copending application filed by me on April 24th, 1918, Serial 50 No. 230,446. This bearing construction consists of a ball bearing support at each end of the shaft, the inner end of the shaft being supported in a recessed adjustable nut 25 carrying a plurality of bearing balls 26. 55 The other end of the shaft is supported in an adjustable nut or stud 27 carrying a plurality of bearing balls 28 yieldingly held against the shaft by means of a 60 slideable plug 29 acted upon by a helical spring 30 which tends to press the plug 29 and bearing balls toward the shaft and automatically take up any wear as it occurs. This shaft 31 is preferably hexagonal and cone-shaped at its ends so as to set properly 65 against the bearing balls. The shaft is pref-

erably of this shape so as to more securely carry the armature 32 and multiple-contact operating plate 33. The armature 32, (Fig. 4) is depressed in the middle so as to embrace the shaft 31, the free ends of the 70

armature being bent toward and into operative relation with the operative ends of the cores and corresponding permanent magnets. In order to prevent sticking of the armature and pole pieces, and effect a smoother operation thereof, I provide anti-sticking devices in the nature of yieldable German silver fingers 34 which are secured at one end of the armature by means of screws 35 while the free ends pass through the armature so as to engage the pole pieces before touched by the armature, the resiliency of these fingers 34 being very effective in preventing sticking of the parts due to residual mechanism. These fingers also effect a more quiet and smooth action of the armature.

The operating shaft 31 also carries a multiple-contact operating-plate 33 which, like the armature, is depressed along the middle as shown in Fig. 5, thereby bringing the multiple-contacts 36 carried by the common contact plate 37 in a line radial to the axis of rotation of the shaft. This gives a good continuing contact during the slight movement of the armature while the contacts are closed. In the present device the contacts are kept normally open so as to prevent discharge of the battery out over the line should the line current be shut off and therefore I bias the armature preferably by means of a weighted member 38 which is sufficient to overcome the tendency of the permanent magnets to improperly bias the armature. Although this bias could be obtained by spring tension I prefer the weight as its action is always the same and thus the frequency of vibration of the armature does not vary.

Cooperation with the contacts 36 are a number of contacts 39 supported by an insulating mounting plate 40 which is suitably carried by a pair of threaded studs 41 and clamping nuts 42, the studs being secured to a bracket 43 fastened to the base. This bracket 43 together with its associated bracket 44 also supports the shaft and spool bracket 21. Bracket 44 is adapted to carry a corresponding set of contacts 36 to cooperate with the adjacent side of the plate 33, to take the other half of the wave. For 110 such a structure reference is to be had to my first said application Serial No. 139,397.

115 By means of the adjusting device just described, the contacts 39 may be adjusted to properly cooperate with the movable contacts 36, the arrangement of the threaded studs and nuts permitting adjustment of the contacts 39 toward or away from the movable contacts 36 and in proper alignment therewith. It is quite important that the 120

contacts operate simultaneously so as to make and break at the proper point in the current wave and it will be apparent that a very close adjustment of the contacts may be secured with the adjustment shown.

I have found that a current of about $1\frac{1}{2}$ amperes through each of the pairs of contacts 36, 39 will not harm the contacts even though they do not operate exactly in step. Thus with the six multiply connected contacts, as provided in the present device, the machine can have an output of about 9 amperes without injury to the contacts themselves irrespective of any faulty operation. However, the output can be varied by changing the number of pairs of contacts 36 and 39.

In Fig. 6 is shown diagrammatically a method of connecting up the machine for charging a storage battery from an ordinary 110 volt 60 cycle line circuit. In this diagram the various parts have reference characters corresponding to the reference characters indicated in Figs. 1 to 5. The contacts 39 it will be noted are each connected through a resistance device, preferably a lamp 12, so as to reduce the flow through each set of contacts to one and one-half amperes.

The lamp circuits are connected in multiple by the common strip 13. The polarized electromagnet 15, 16 is connected in series with a condenser 14 and across the line circuit 45 through a switch 47. The capacity of the condenser 14 is properly proportioned to the resistance and impedance of the electromagnet so that the armature 32 and contact operating plate 33 step in phase with the alternating current and thus the contacts 36, 39 when properly adjusted, make and break at the proper point in the current wave. Thus, at each complete cycle, a current impulse is transmitted through the charging circuit including the storage battery 46 and switch 48. The charging current flow through this battery is uni-directional, that is in one direction, as the contacts 36, 39 simply operate upon one-half of the cycle. Thus the continued operation of the machine effects a charging of the storage battery by converting the alternating current source 45 into a uni-directional current.

Having thus described my invention, what I claim as new and desire to obtain by Letters Patent is:

1. A device of the character described comprising an electromagnet, an armature adapted to be vibrated thereby, a shaft carrying said armature mounted for pivotal movement, a contact plate carried by the shaft and reciprocated therewith, a plurality of contacts simultaneously cooperating with the contacts on said plate, and means for maintaining said plate normally biased and

thus free of the contacts, said means having a uniform effect on the period of vibration of the armature.

2. A device of the character described comprising an electromagnet, an armature adapted to be vibrated thereby, a shaft carrying said armature mounted for pivotal movement, a contact plate carried by the shaft and reciprocated therewith, a plurality of contacts simultaneously cooperating with the contacts on said plate, and means for overcoming the polarizing effect and maintaining said plate normally biased and thus free of the contacts, said means having a constant effect on the period of vibration of said armature.

3. A device of the character described comprising a polarized two-pole electromagnet, an armature mounted for pivotal movement about a central pivot and having an end operatively related to each electromagnet pole so as to be vibrated thereby, means tending normally to swing said armature in one direction and a non-magnetic yieldable anti-sticking device carried at each end of the armature cooperative with the corresponding pole.

4. A device of the character described comprising a two-spool polarized electromagnet, a plate connecting the operating poles thereof, a shaft pivotally carried by said plate transverse of said poles, an armature carried at one end of the shaft and cooperative with the electromagnet, and a multiple-contact operating plate carried at the other end of said shaft.

5. A device of the character described comprising a polarized electromagnet, a mounting plate secured to the operating poles thereof, bearing brackets positioned transverse of the said poles, an operating shaft pivotally supported between said brackets, an armature at one end of said shaft adjacent said poles and a multiple contact operating plate carried at the other end of the shaft, both the armature and the contact plate being positioned between the bearing brackets.

6. A device of the character described comprising a polarized electromagnet including parallel spools, a mounting plate connecting the operating poles of the spools, an elongated transversely positioned shaft carried by the mounting plate, an armature at one end of the shaft and a contact operating plate at the other end of the shaft, said contact plate lying parallel to the shaft and mounting plate, a contact carrying plate lying parallel to the contact operating plate, and means for adjusting the contact carrying plate toward and away from the contact operating plate.

7. A device of the character described comprising a polarized electromagnet including parallel spools, a shaft disposed per-

pendicular to said spools, an armature for the electromagnet at one end of the shaft, a plurality of contacts, an elongated contact operating plate parallel to said shaft carried at the other end of the shaft, and weighted means overcoming the polarizing effect and maintaining said plate normally biased and thus free of the contacts.

8. A device of the character described comprising an electromagnet, a transverse plate connecting the operating poles thereof, a shaft pivotally supported by the plate transverse of the operating poles, an armature carried by the shaft, and a multiple contact operating plate centrally depressed to embrace the shaft so as to provide a contact operating surface radial to the axis of rotation.

9. A device of the character described comprising a polarized electromagnet, an armature operatively related to the poles thereof, and resilient anti-sticking springs carried by and projecting through the armature for cooperation with the magnet poles.

10. A device of the character described comprising a polarized electromagnet, a shaft suitably supported transverse the face of the operating poles thereof, an armature centrally depressed to embrace the shaft to firmly hold the armature on the shaft and bring the operating ends of the armature in close proximity to the faces of the operating poles.

11. A device of the character described comprising an electromagnet, a pivotally mounted biased armature adapted to be vibrated thereby, a shaft carrying said armature, a contact plate carried by said shaft and vibrating with said armature and a plurality of contacts operated by said plate.

12. A device of the character described comprising a polarized electromagnet, a pivotally mounted contact plate vibrated thereby, a plurality of contacts operable by said plate and means for maintaining said plate normally biased and free of the contacts, said means having a constant effect on said armature.

13. A device of the character described comprising a polarized electromagnet, an armature operatively related to the poles thereof, and anti-sticking devices carried by said armature said anti-sticking devices com-

prising light springs secured to the rear side of said armature and having end portions 55 projecting through said armature for cooperation with the magnet poles.

14. A device of the character described comprising an electromagnet, an armature adapted to be vibrated thereby, a shaft carrying said armature mounted for unrestrained pivotal movement, a contact plate carried by the shaft and reciprocated therewith, a plurality of contacts simultaneously cooperating with said plate, and means for 60 maintaining said plate normally biased and thus free of the contacts, said means comprising a weight secured to said plate adjacent one of the side edges thereof.

15. A device of the character described 70 comprising a polarized electromagnet, an armature adapted to be vibrated thereby, a shaft carrying said armature mounted for unrestrained pivotal movement, a contact plate carried by the shaft and reciprocated 75 therewith, a plurality of contacts simultaneously cooperating with said plate, and means for overcoming the polarizing effect and maintaining said plate normally biased and thus free of the contacts, said means comprising a weight secured to said plate adjacent one of the side edges thereof.

16. In a rectifier, a polarized electromagnet, an armature, a shaft for pivotally carrying said armature, a fixed contact, a 85 contact on said armature cooperating therewith, and means for biasing said armature away from said fixed contact, said means having a uniform biasing effect at all times.

17. In a rectifier, a polarized electromagnet, an armature, a shaft for pivotally carrying said armature, a fixed contact, a contact on said armature cooperating therewith, and gravity operated means for biasing said armature away from said fixed 95 contact.

18. In a rectifier, a polarized electromagnet, an armature vibrated thereby, a fixed contact, a contact on said armature cooperating therewith, and gravity operated 100 means for biasing said armature away from said fixed contact.

In witness whereof, I hereunto subscribe my name this 16th day of April, A. D., 1918.

OSCAR M. LEICH.
